FLUID ROUTING

Lars Hanson, Syracuse, N. Y., assignor to Carrier Corporation, Syracuse, N. Y., a corporation of Delaware

Application September 7, 1942, Serial No. 457,599

1 Claim. (Cl. 29—157.3)

This invention relates to methods of fluid routing employed more particularly in connection with shell and tube structures.

The general object of the invention is to provide simple and inexpensive pass partition devices which may readily be inserted between adjacent series of tubes at an end of a shell, said devices being arranged to cooperate with a gasket positioned between a tube sheet and a fluid distributor head so that the devices and gasket will effectively route fluid from the head in a given course through a plurality of series of fluid passes.

A feature of the invention is the provision of relatively flexible partition strips preferably made of material sufficiently ductile to wedge between adjacent tubes and make permanent contact therewith. The result is that subsequent to positioning of such partition strips between desired series of tubes to form a prescribed pass arrangement, the usual gasket and distributor head may be removed, as when necessary for the purpose of cleaning tubes, without disturbing the pass arrangement.

Another feature of the invention resides in the provision of separable and individual partition strips so arranged at the end of a tube bundle that when wedged between desired series of tubes projecting beyond a tube sheet such strips will provide the equivalent of an integral pass arrangement adapted to route fluid in a desired course first through one series of tubes, then through another, and so on. Despite the fact that the strips are initially in separable form, the combination of strips utilized in final positioned form simulates a composite unified partition arrangement. The advantage flowing from this method of positioning strips is that different of the strips may project between series of tubes to different degrees at different points along the strips. Yet, the outside surface of the strips will be substantially in the same plane as an enveloping gasket, on which a distributor head is fitted.

Further features and objects, making for a saving in size of shell, in reduction of submergence losses, in ease of assembly and disassembly, in permanence of partition structure, as well as in economy of replacement when necessary, and in adaptability for desirable rearrangement of passes, will be apparent from the following written description of a typical form of the invention to be read in connection with the accompanying drawings in which:

Fig. 1 is an exploded diagrammatic view of one

end of a shell and tube arrangement fitted with applicant's pass partition device;

Fig. 2 is a fragmentary diagrammatic view, in section, showing the inter-relation between a shell and tube structure equipped with applicant's partition strips and a liquid distributor head applied to the shell;

Fig. 3 is an enlarged detail illustrating the positioning of a partition strip between adjacent tubes projecting from a tube sheet;

Fig. 4 illustrates a partition strip in the form assumed by it when positioned between adjacent groups of tubes; and

Fig. 5 is a section of a strip in which a metal core is surrounded by a more flexible material.

Considering the drawings, similar designations referring to the similar parts, and without regard to scale, which obviously is different in the several views, the description will first have reference more particularly to Fig. 1. Numeral 6 designates a shell of the type used for coolers and condensers in connection with refrigeration systems, although the invention may be applied to shell and tube structures in general. Tube sheet

7 is at the end of the shell, and tubes 8 positioned within the shell have their extremities pass through the tube sheet 7 and project beyond it. While the tubes are shown at one end of the shell, it will be understood that the same arrangement also exists at the other end. Flange piece 9 is provided with bolt holes 10 to which distributor head 11 may be bolted, with gasket 12 positioned between flange 9 and the head 11.

The tube sheet 7 may be separate from the flange piece 9 or, if desired, the flange piece may be integral with and an extension of the tube sheet, so that one piece may actually be employed.

The distributor head is provided with liquid supply and return connections 13. Since it is desirable to route liquid from the supply connection through the tubes in a series of passes, numerous expedients have heretofore been employed for directing the flow of liquid back and forth through the series of tubes. Such expedients have normally embraced the use of partitions within the shell in combination with partition means within the head. This has not only resulted in expensive construction of the shell but has also necessitated employing a larger shell than need be utilized with applicant's invention. Even when the shell itself was not provided with partition means but only the head arranged with devices for segregating different groups of tubes, the construction was expensive and the increased

size of the shell also brought about reduced efficiency.

Applicant overcomes these and other objections, and provides for increased efficiency, flexibility of operation, at reduced cost, by the provision of partition strips 14 preferably made of soft material which may readily be corrugated and positioned between adjacent rows or groups of tubes. As generally illustrated in Fig. 1, the partition strips are inserted between rows or groups of tubes, as desired, to form a series of passes. Obviously, the strips will be inserted at both ends of the shell so that water or other fluid flowing through one pass, as formed by the partition strips at one end, will then be directed to another pass depending upon the positioning of the strips at the other end, and so on, until the fluid is finally discharged from the shell.

As shown in detail in Figs. 2 and 3, strip 14 is inserted between adjacent tubes 8, whose ends 15 project beyond tube sheet 7. The ends of the tubes may be rolled in order snugly and frictionally to engage the strip 14. In Fig. 3 the tube ends 15 are shown rolled to a relatively exaggerated degree, but it will be understood that even without rolling the protruding tube ends, the strip 14 will be frictionally engaged between adjacent series of tubes. It will be appreciated that although the tube ends are shown projecting from the tube sheet a relatively small distance, the extent of protrusion beyond the tube sheet may be increased as desired. In fact, this is often of advantage in the event it is required to insert partition strips 14 to varying degrees at different points, as may be necessary in the event of irregularities in the width of the strips, or for other reasons.

The head 11 is provided with partition walls 16 designated to engage strips 14 in order to provide the desired course of flow through the tube bundle in a series of specified passes.

In Fig. 5 is shown a section of a modified form of partition strip in which the core 17 may be of metal to provide a firm characteristic while enveloping material 18 has a ductile or flexible characteristic. While a metal core and a rubber-like coating may be acceptable under some conditions, the materials may be changed depending upon the service to be performed, and the selection may be varied in the light of corrosive characteristics of the fluids to be handled.

Since there is no need for leaving spaces between rows or groups of tubes, as was formerly required in order to provide for desired flow in a series of passes, the tubes can now be packed closely together and the spacing between tubes can be uniform for the entire tube sheet. The height of partition strips 14 can be selected with respect to the thickness of gasket 12 so that the gasket and outside tips of the partition strips will be substantially in the same plane. Thus, if the tips of partition walls 16 and the flange portion of head 11 are in the same plane there will be good contact at all points. However, if there are irregularities in the lengths of the tip ends of partition walls 16, or other irregularities, the contacts will still be made since the partition

walls with their relatively wide tips may press upon strips 14 and squeeze them to varying degrees into the small channels between adjacent tubes. The great advantage of such method of obtaining a snug fit is that while this always assures easy and assured channeling, the strips are so narrow that an obstructed entrance to the tubes adjacent to the partition strips is always maintained.

By changing the position of the strips an infinite selection of passes can be made without changing the shell or tube sheet. The only change required would be in providing a new head with partition walls arranged to conform with the new positioning of the strips. Thus, shell and tube structures could easily be converted in the field to provide different arrangement of passes at very small expense and with little waste of time.

Since the head could be removed without disturbing the pass arrangement, servicing may be accomplished without removing the strips.

The close spacing of the tubes, which may be employed with applicant's partition strips, not only reduces the size of shell required for a given capacity, but also reduces the amount of liquid refrigerant required for complete flooding in the case of flooded coolers. This reduces the liquid head, which in turn decreases temperature losses. That is, submergence losses are held to a minimum.

Since many changes may be made in details of application, and since the scope of the invention is not limited to particular shell and tube devices, it will be understood that applicant makes no limitations with respect to methods or manner of application of the invention as defined by the appended claim.

I claim:

40. A method of directing the flow of fluid in a desired pass arrangement through a shell and tube structure consisting in providing a shell with tube sheets, positioning a series of tubes within the shell with the spacing between adjacent tubes being less than half the diameter of a tube, projecting said tubes through the tube sheets with the tube ends extending beyond the tube sheets, expanding the projected ends so that they flare outwardly from the tube sheets, frictionally holding between projecting tube ends separate strips of ductile material of a width considerably greater than the projecting tube ends, so that the strips extend beyond the tube ends and positioning the strips between desired series of projecting ends to divide the tubes into a prescribed arrangement of passes, applying adjacent a tube sheet a distributing header having rigid partitioning walls corresponding in interpositioning and in linear extent with said strips so that the partition walls abut the strips, and exerting pressure on the header to cause the partitioning walls to exert pressure upon and expand the portions of the strips held between projecting tube ends to effect interlocking of the same with the tube ends.
